Primary Examiner — Michael A. Pratt*Assistant Examiner* — Wendy L Arminio*(74) Attorney, Agent, or Firm* — David R. Crichton(57) **CLAIM**

The ornamental design for a packaging tray for a medical device, as shown and described.

DESCRIPTION

FIG. 1 is a perspective view of a packaging tray for a medical device, showing our new design;

FIG. 2 is a top view of the packaging tray for a medical device shown in FIG. 1;

FIG. 3 is a side elevation view of the packaging tray for a medical device shown in FIG. 1;

FIG. 4 is a bottom view of the packaging tray for a medical device shown in FIG. 1;

FIG. 5 is a side elevation view of the packaging tray for a medical device shown in FIG. 1;

FIG. 6 is a front view of the packaging tray for a medical device shown in FIG. 1; and,

FIG. 7 is a rear view of the packaging tray for a medical device shown in FIG. 1.

1 Claim, 4 Drawing Sheets(56)
